MOWER RIDING ATTACHMENT

Ellsworth F. Brewer, Milwaukee, Wis., assignor to E. F.
Brewer Company, a corporation of Wisconsin

Application February 1, 1956, Serial No. 39,997

Term of patent 14 years

(Cl. D40—1)

Fig. 1 is a side and top perspective view of a mower riding attachment embodying my new design; and

Fig. 2 is a front and top perspective view of the mower riding attachment.

The broken line portion of the drawing disclosure is depicted for illustrative purposes only.

I claim:

The ornamental design for a mower riding attachment, substantially as shown and described.
